(57) **CLAIM**

The ornamental design for a fishing spoon, as shown.

DESCRIPTION

FIG. 1 is a perspective view of the fishing spoon showing my new design

FIG. 2 is a front elevational view thereof;

FIG. 3 is a rear elevational view thereof;

FIG. 4 is a side elevational view, the opposite side being a mirror image thereof;

FIG. 5 is a top view thereof;

FIG. 6 is a bottom view thereof; and,

FIG. 7 is a perspective view of a second embodiment the shape and configuration of which is consistent with FIGS. 1-6, except for the shape of the rear end of the fishing spoon. The broken line showing of connectors is for illustrative purposes only and forms no part of the claimed design.
